US00D839185S

(12) **United States Design Patent** (10) **Patent No.:** **US D839,185 S**
Jiang (45) **Date of Patent:** **** Jan. 29, 2019**

(54) **POWER BANK**

(71) Applicant: **OUTXE POWER TECHNOLOGY CO., LIMITED**, Kln (HK)

(72) Inventor: **Meng Hua Jiang**, Kln (HK)

(**) Term: **15 Years**

(21) Appl. No.: **29/617,232**

(22) Filed: **Sep. 12, 2017**

(51) LOC (11) Cl. **13-02**

(52) U.S. Cl.

USPC **D13/107**

(58) **Field of Classification Search**

USPC D14/250; D13/102, 103, 107, 108
CPC H04B 1/385; H04M 1/04; H04M 1/6033;
B29L 2031/3437

See application file for complete search history.
